TELEPHONE SET

Henry Dreyfuss, South Pasadena, Calif., and Donald M. Genaro, Haworth, N.J., assignors to Bell Telephone Laboratories, Incorporated, Murray Hill, N.J., a corporation of New York

Filed Feb. 2, 1968, Ser. No. 10,421

Term of patent 14 years

Int. Cl. D14—03

U.S. Cl. D26—14

FIG. 1

FIG. 2

FIG. 3

FIG. 4

FIG. 5

FIG. 6

FIG. 1 is a side perspective view of a telephone set showing our new design;

FIG. 2 is a side perspective view thereof, with the handset free of its base and in an alternate position;

FIG. 3 is a plan view as seen from the top of FIG. 1;

FIG. 4 is a side elevation thereof;

FIG. 5 is a top plan view of the telephone base, shown for clarity of illustration; and

FIG. 6 is an end elevation as seen from the right of FIG. 1.

The dominant features of our design reside in the portion shown in full lines.

We claim:

The design for a telephone set, substantially as shown and described.
